(74) *Attorney, Agent, or Firm* — Birch, Stewart, Kolasch & Birch, LLP

(57) **CLAIM**

The ornamental design for a display module, as shown and described.

DESCRIPTION

FIG. 1 is a front, right perspective view of the display module showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof; and,

FIG. 8 is a rear, left perspective view thereof.

FIG. 9 is an exploded front, right perspective view thereof;

FIG. 10 is a front, right perspective view of a second embodiment thereof;

FIG. 11 is a front view thereof;

FIG. 12 is a rear view thereof;

FIG. 13 is a left side view thereof;

FIG. 14 is a right side view thereof;

FIG. 15 is a top plan view thereof;

FIG. 16 is a bottom view thereof;

FIG. 17 is a rear, left perspective view thereof; and,

FIG. 18 is an exploded front, right perspective view thereof.

The broken lines depict portions of the display module that form no part of the claimed design.

1 Claim, 18 Drawing Sheets

Matter enclosed in heavy brackets [ ] appears in the original patent but forms no part of this reissue; matter printed in italics indicates the additions made by reissue.
